UNITED STATES PATENT OFFICE.

CHARLES ERNEST PAGE, JACK FINDLAY PAGE, AND CHARLES NORMAN PAGE, OF CHRISTCHURCH, NEW ZEALAND.

FLUSHING CISTERNS.

Application filed July 5, 1923. Serial No. 649,623.

To all whom it may concern:

Be it known that we, CHARLES ERNEST PAGE, JACK FINDLAY PAGE, and CHARLES NORMAN PAGE, all subjects of the King of Great Britain, and all residing at 29 Dyer's Pass Road, Cashmere, Christchurch, in the Dominion of New Zealand (whose post-office addresses are 29 Dyer's Pass Road, Cashmere, Christchurch, New Zealand), have invented new and useful Improvements in Flushing Cisterns, of which the following is a specification.

This invention relates to a flushing device for water-closets and the like, the object of the invention being to provide a novel, simple and reliable device of this nature which will be silent in action and wherein the release of the water from the cistern will be effected by the opening of a valve or plug which may be positioned close to the basin in order to minimize noise.

In order that the nature of the invention may be clearly understood, it will now be explained with reference to the accompanying drawings in which:—

Fig. 1 is a sectional elevation of a cistern equipped in accordance with the present invention, the positions of the parts when the valve is closed being shown in full lines while the positions of such parts when the valve is open being indicated in dotted lines, and,

Fig. 2 is a plan view of such cistern.

1 is a containing vessel or cistern provided with a ball-cock 2 or other appropriate means whereby water is admitted to fill such cistern to a suitable level as represented by the line A—A, such cistern being connected with the basin by means of a flush-pipe 3.

40 In order to intercept the flow of water from such cistern down the flush-pipe, there is provided a valve or plug 4 adapted to close upon a suitable seat 5. In the case of a cistern arranged at a height above the basin, and connecting with the latter by means of a long flush-pipe the said valve 4 and its seat 5 will preferably be arranged in the lower portion of such flush-pipe, in order to be near the basin. In the case of a cistern

45 which is itself intended to be mounted low down or as near as practicable to the basin, thus reducing the flush-pipe to virtually a bend or short connection between such cistern and basin, the said valve and its seat

will preferably be arranged at the upper 55 end of such pipe as here shown.

The said valve is adapted to be opened by lifting it from its seat for which purpose such valve is provided with an upwardly extending wire or connection 6.

According to the present invention for the purpose of controlling the opening and closing of the valve there is provided within the cistern 1, and suitably fulcrumed as upon a horizontal axis 7, a bell-crank lever 65 one arm 8 of which is adapted normally to extend in a horizontal or virtually horizontal direction and to which arm is attached the connection 6.

The other arm 9 of the lever is adapted, 70 when the latter occupies its said normal position, to extend upwardly in an approximately vertical direction from its said fulcrum and is provided with a suitable weight 10, while attached to the horizontal arm 8 75 is a body 11 composed of metal or other suitable material and which is preferably made hollow in order that its weight may be adjusted by filling it to the required extent with water or other appropriate substance. 80 The arrangement is such that when the cistern is filled with water and the said lever occupies its said normal position, as here shown in full lines, the valve 4 will be closed upon its seat 5 while the weight 10 and body 11 will exercise no effective action to turn the lever which latter will in consequence remain at rest.

When a flush is desired however, the lever will be turned manually into the position 90 shown in dotted lines thereby raising the valve and so permitting the water to be discharged down the flush-pipe. When the lever is in this position the upward arm 9 will lie at an angle to the vertical thereby 95 placing its said weight 10 in such a position as to exert a control in maintaining the lever in this position when the manual operation is relaxed or removed.

This control of the lever by the weight 10 100 is opposed by the body 11 upon the other arm but the weight of such body while submerged in the water is insufficient to overcome the said control by the weight 10.

The lever will therefore remain in this 105 position maintaining the valve open and so permitting the discharge of the water to continue.

This condition of affairs will therefore continue until the water-level in the cistern has been lowered to a point such as that represented by the line B—B at which the body 11 will be partly or wholly uncovered.

When this takes place the body 11 in consequence of the loss or reduction of its buoyant support by the water, will have its effective weight increased to such an extent 10 as to successfully oppose the control of the weight 10 and thus return the lever to its previous or full-line position thereby permitting the valve 4 to again close upon its seat 5.

15 Suitable means of manipulation will be provided for enabling the said manual turning of the lever into its valve-opening position to be effected. As here shown such means consist of a rod 12 disposed in a substantially horizontal direction and slideable through an opening or bush in one of the walls of the cistern, the inner end of such rod being operatively connected with the arm 9 of the lever while the outer or reverse 20 end of such rod is provided with a suitable knob or button 13 adapted to receive a pressure from the thumb or fingers of the operator.

As previously mentioned the admission of 30 the water to the cistern is governed by means of a ball-cock 2. In order to prevent the arm 14 of such ball-cock from sinking so far as to foul the arm 8 of the lever or any parts connected therewith, there is provided 35 a limiting stop consisting of a rod 15 extending horizontally across the interior of the cistern and at such a position as to receive and support the said arm 14 when the latter sinks in consequence of the reduction 40 of the water level in the cistern occasioned by the flush as already explained.

In order to provide a simple and convenient means for fulcruming the said bell-crank lever, upon the inner surface of the 45 two side walls of the cistern are formed a pair of inwardly projecting U-shaped flanges 16 adapted to receive the said axis 7 of such lever.

Similar U-shaped flanges 17 are also provided to receive and support the said rod 15.

We claim:

1. A flushing cistern comprising a containing vessel, means for admitting water thereto, a valve governing the discharge of 55 water from the said vessel, a bell crank lever fulcrumed in said vessel to be turnable in a vertical plane with one arm of the bell crank extending vertically and the other arm of

the bell crank extending in a substantially horizontal plane, means operatively connecting the horizontal arm of the lever with the aforesaid discharge valve, a weight carried by the vertical arm of the lever to maintain said lever in valve-opening position when moved thereto, a body 60 carried by the horizontal arm of the lever arranged when submerged to ineffectively oppose said control of the lever by said weight, but on becoming emerged to overcome said control and turn said lever to its 65 valve closing position, and means for moving the lever to valve opening position comprising a rod mounted to slide through an opening in the containing vessel and equipped with handle means at its outer end, stop 70 means carried by an intermediate portion of the rod for engaging the inner wall of the containing vessel, and a pivotal connection between the inner end of the rod and the weighted arm of the lever. 75

2. A flushing cistern comprising a containing vessel a valve for admitting water thereto, a pivotally mounted arm equipped at one end with a float and having its opposite end in operative engagement with said valve to control opening and closing of the latter, a valve to govern the discharge of water from said vessel, a bell crank lever fulcrumed in said vessel to be turnable in a vertical plane and having one upward 90 arm and one substantially horizontal arm, means operatively connecting said lever with the aforesaid discharge valve, manually operable means for turning said lever into the position to open said valve, 95 a weight upon said upward arm operating to maintain said lever in said valve open position, a body carried by said horizontal arm and arranged when submerged to ineffectively oppose said control of the lever by said weight, but on becoming emerged to overcome said control and turn said lever to its valve closing position and a stop arranged to be engaged by the float arm to prevent the latter from sinking so 100 far as to foul the lever.

In witness whereof, we have hereunto set our hands at Christchurch, New Zealand, this first day of June, 1923.

CHARLES ERNEST PAGE.

JACK FINDLAY PAGE.

CHARLES NORMAN PAGE.
